Application January 9, 1941, Serial No. 97,941

Term of patent 14 years

To all whom it may concern:

Be it known that I, Meredith Stewart Ireys, a citizen of the United States, residing in Lancaster, county of Lancaster, and Commonwealth of Pennsylvania, have invented a new, original, and ornamental design for a Bottle or Similar Article, of which the following is a specification, reference being had to the accompanying drawing, forming a part hereof, and of which—

Figure 1 is a view in front elevation of a bottle or similar article, showing my new design;

Figure 2 is a view in rear elevation thereof; and

Figure 3 is a developed view of a portion of

the bottle or similar article shown in Figures 1 and 2, showing the ornamentation of my new design.

The dominant features of the design reside in the ornamentation portion shown in solid lines.

The bottle is of generally rounder contour.

This application is a continuation in part of my application Serial No. D-96,248, filed November 1, 1940.

I claim:

The ornamental design for a bottle or similar article, substantially as shown and described.
